PACKAGE FOR RAYON CONES OR
THE LIKEBen M. Williams, St. Louis, Mo., assignor to
Robert Gaylord, Incorporated, St. Louis, Mo.,
a corporation of Missouri

Application March 2, 1935, Serial No. 8,996

7 Claims. (Cl. 206—65)

My invention relates to a package for shipping, storing, and handling articles such as rayon cones, which require more than ordinary protection against abrasion during such operation owing to their delicate texture and liability to fraying, or other injury by contact either with each other or with the walls of the containers.

The object of my invention is to provide such a package which will be simple in construction and inexpensive to manufacture and which will be sufficiently rigid and insure the necessary protection against abrasion.

Another object of my invention is to provide a package which will comprise a plurality of individual holders contained in a master carton, each holder carrying a number of cones, or like articles, whereby the distribution of the articles to weaving, knitting, or other machines, is facilitated.

In the accompanying drawings, which illustrate one form of package made in accordance with my invention, Figure 1 is a plan view of one of the blanks from which the holders are formed; Figure 2 is a plan view of the other holder blank; Figure 3 is a perspective view of one of the holders; Figure 4 is a vertical section through a portion of a holder showing a cone in position therein; Figure 5 is a top view of a package comprising a plurality of holders, the master carton and two of the holders being in section and the other two in plan; and Figure 6 is a side view of the package shown in Figure 5, the master carton and two of the holders being shown in section and the other two in elevation.

Each holder is formed from a main blank, shown in Figure 1, and a secondary or partition blank, shown in Figure 2. The main blank consists of a rectangular sheet of material, such as fiberboard, either solid or corrugated. The blank is divided by means of transverse crease lines 1, 2, 3, 4, 5 and 6 into a bottom panel 7, a pair of side panels 8 and 9, a pair of top panels 10 and 11, a partition wall 12 carried by top panel 10, and a locking strip 13 carried by top panel 11. Formed in the bottom panel are four circular openings 14. Formed in each of the top panels 10 and 11 are a pair of circular openings 15, which openings register with the openings 14 when the holder is in assembled form. The top panels are each provided with a partially detached lifting tab 16, that on the panel 10 being adjacent the crease line 5 and that on panel 11 being adjacent the crease line 2. The top panel 11 is also provided with a semi-detached releasing tab 17 adjacent the crease line 1. The partition wall

12 is provided with a slot 18 for interlocking with the partition plate 19 which is provided with a slot 20 similar to the slot 18 but somewhat wider as it must receive both the partition wall 12 and the locking strip 13.

In Figure 4 I have shown one of the cones adapted to be contained in the package. This cone consists of material 21, such as rayon, wound upon a tapered hollow spindle 22. At the lower end, this spindle projects slightly below the cone to form a base 23 of the same diameter as one of the openings 14. The upper end of the spindle projects beyond the cone somewhat farther than the base to provide a highly polished part 24, known as the "button", fitting snugly into openings 15.

To assemble one of the holders the bases of two cones are placed in the opening 14 of the blank adjacent the crease line 4. The partition plate 19 is now interlocked with the partition wall and the side wall 8 bent up at right angles to the bottom panel. The top panel 10 is now bent over parallel to the base, and finally the partition wall is bent down parallel with the side wall, one end of the partition plate extending between the two positioned cones. The buttons of the cones will project through the openings 15 of the top panel 10. The bases of two more cones are now placed in the remaining openings 14, the side panel 9 bent up, the top panel 11 bent over, and the locking strip forced down into engagement with the slot 20 of the partition blank. As thus assembled, the holder is as shown in Figure 3, except that in this figure the cones are omitted.

In Figures 5 and 6 I have shown a number of holders assembled in a master carton 25. For the purpose of illustration I have shown eight holders in two rows or tiers of four each, but the number of holders composing the package may be varied and will usually be greater than that shown. In placing the holders in the carton, each holder is turned at an angle of 90 degrees relative to the adjacent holders, so that the open side of one holder will be covered by a closed side (panel 8 or 9) of the adjacent holder. The tabs 16 and 17 of the bottom, or any intermediate tier, will be held flat by the tier resting upon it and the buttons 24 projecting from the upper faces of the holders will enter the hollow bases of the spindles of the tier resting upon it. To provide for the reception of the buttons of the upper tier, I place upon it a pad 26 having therein openings 27 registering with the openings 15 of said upper tier. These openings 27 receive the buttons

- of the upper tier. The carton 25 has been conventionally shown as it may be of any well-known construction. The lifting tabs 16 serve as handles to withdraw the holders from the carton, an operation which would otherwise be difficult, if not impossible. They are also of convenience when distributing the holders. The tabs 17 serve as convenient means for withdrawing the locking strips 13 to open the holders.
- 10 Having fully described my invention, what I claim as new and desire to secure by Letters Patent of the United States is:
1. In a device of the class described, a carton, a plurality of cone holders in said carton, each 15 holder having a pair of opposed open sides and a pair of opposed closed sides, an open side of each holder abutting the closed side of an adjacent holder.
  2. A cone holder comprising a bottom panel having a plurality of openings to receive cone bases, a pair of side panels, a pair of top panels each provided with openings for cone buttons, a partition wall carried by one of said top panels, and locking means carried by the other top 25 panel.
  3. A cone holder comprising a bottom panel having a plurality of openings to receive cone bases, a pair of side panels, a pair of top panels each provided with openings for cone buttons, a 30 partition wall carried by one of said top panels, a partition plate interlocking with said partition wall, and a locking strip carried by the other top panel.
  4. A cone holder comprising a bottom panel having a plurality of openings to receive cone bases, a pair of side panels, a pair of top panels each provided with openings for cone buttons,
- a semi-detached tab on each top panel forming lifting means, a partition wall carried by one of said top panels, and locking means carried by the other top panel.
5. A cone holder comprising a bottom panel having a plurality of openings to receive cone bases, a pair of side panels, a pair of top panels each provided with openings for cone buttons, a partition wall carried by one of said top panels, a locking strip carried by the other top panel, 10 and a releasing tab on said latter named top panel adjacent the locking strip.
6. A cone holder comprising a bottom panel provided with openings for cone bases, side panels carried by two sides of the bottom panel, a top 15 panel carried by each side panel, said top panels being provided with openings for cone buttons, a partition plate provided with a slot, a partition wall carried by one top panel and interlocking with said partition plate, and a locking strip 20 carried by the other top panel and entering the slot in said partition plate.
7. A cone holder comprising a bottom panel provided with openings for cone bases, side panels carried by two sides of the bottom panel, a top 25 panel carried by each side panel, said top panels being provided with openings for cone buttons, each top panel being provided with a lifting tab positioned adjacent a side wall, a partition plate provided with a slot, a partition wall carried by one top panel and interlocking with said partition plate, and a locking strip carried by the other top panel and entering the slot in said partition plate.
